US0D1077466S

(12) United States Design Patent (10) Patent No.: US D1,077,466 S
(45) Date of Patent: * Jun. 3, 2025

(54) BEACH BAG

(71) Applicant: Dongjie Chen, Quanzhou (CN)

(72) Inventor: Jiao Wu, Chongqing (CN)

(73) Assignee: Dongjie Chen, Quanzhou (CN)

() Term: 15 Years

(21) Appl. No.: 35/520,996

(22) Filed: Apr. 24, 2024

(80) Hague Agreement Data

Int. Filing Date: Apr. 24, 2024

Int. Reg. No.: DM/236981

Int. Reg. Date: Apr. 24, 2024

Int. Reg. Pub. Date: May 24, 2024

(30) Foreign Application Priority Data

Jan. 16, 2024 (CN) 202430026608.6
